UNITED STATES PATENT OFFICE.

THOMAS C. GIBSON, OF WASHINGTON, DISTRICT OF COLUMBIA.

CAR-COUPING.

SPECIFICATION forming part of Letters Patent No. 487,367, dated December 6, 1892.

Application filed September 1, 1892. Serial No. 444,812. (No model.)

To all whom it may concern:

Be it known that I, THOMAS C. GIBSON, a citizen of the United States, residing at Washington, in the District of Columbia, have invented certain new and useful Improvements in Car-Couplers; and I do hereby declare the following to be a full, clear, and exact description of the invention, such as will enable others skilled in the art to which it appertains to make and use the same.

This invention has relation to automatic car-couplers; and it consists in certain peculiarities in the construction, arrangement, and combination of the several parts, substantially as hereinafter described, and particularly pointed out in the subjoined claims.

In the accompanying drawings, illustrating the invention, Figure 1 is an inverted plan view, partly in section and with parts broken away, of two couplers constructed in accordance with my invention, said couplers being shown as coupled together. Fig. 2 is a front view of one of my improved couplers, showing the parts thereof in the position they occupy when uncoupled and ready to be coupled. Fig. 3 is a detail perspective view of the means for turning the coupling-rod. Fig. 4 is a perspective view of the latch.

The same letters of reference designate the same parts in the several figures.

A designates one member of my improved coupler, and B the other member thereof.

The member A consists of a rod C, which passes through openings in beams or plates C³, which are secured to the car-body at different points and depend therefrom. Said rod C has at its forward end a head c, which projects outward from opposite sides thereof, and it is also provided with an encircling coil 40 spring C', which tends to keep it normally in its foremost position and yet permits it to have an endwise movement for an obvious purpose, and with a weight C², which tends to keep it in such position that its head c will be horizontal, which position said head occupies when cars provided with my coupler are coupled together thereby. This rod is also provided with projections c² and c³, the former serving to limit the endwise movement

of said rod and the latter providing an abutment for said spring C'.

The member B consists of a draw-head D, having its draw-bar d extending loosely through openings in the supporting beams or plates D². This draw-bar is encircled by a spring d', which tends to keep the draw-head in its foremost position, and has a projection d², which provides an abutment for said coiled spring.

The draw-head D (shown in the drawings) consists of a horizontal plate D', having a suitable opening d''' at its forward end and a vertical plate D'' of suitable length secured near its upper end to said plate D' and having a vertical opening d'' of substantially the same width as the body of said rod C, but of considerably-greater length than the diameter of the same. The openings d'' and d''' jointly form the mouth of the draw-head, and it will be observed that they are such relative widths as to leave shoulders d⁴ within the draw-head at the rear of said opening d''.

In operation the forward end of rod C enters said opening d'', and its head c is then automatically turned to horizontal position and engages the rear sides of shoulders d⁴, thus coupling the cars together.

I will now describe a simple and practical means for keeping the rod C in such position that its head may enter or leave said opening d'' and for automatically releasing the rod at a proper time, so as to permit the weight C² on said rod to drop by gravity and turn the rod to a position at right angles to that which it formerly occupied.

F designates a rock-shaft, which is journaled in suitable bearings and is provided with an operating-lever secured to one of its ends and also with a disk G or other suitable device, which is connected with the side of rod C opposite weight C² by means of a loose chain G'. To uncouple the cars, it is only necessary to turn this lever from a horizontal to a vertical position, which causes the rock-shaft to pull upon rod C with such force as to overcome the power of weight C² thereon, thus partly rotating said rod and bringing its head c into position to leave the draw-head.

When said lever is turned to vertical position, it is automatically engaged by a spring-pressed latch I, the forward end of which projects through an opening in the front plate or beam C³ and has at one side a hook i. This latch by engaging the lever holds the forward end of the rod C in position to enter the draw-head D. Said latch has at its front end, on the side thereof opposite the hook i, a projection I', which is of such length that it will be engaged by draw-head D of an approaching car when the headed end of rod C has reached a position immediately at the rear of shoulders d⁴, and said latch thereby being forced out of engagement with said lever, thus allowing the weight to act in the manner above described to turn the coupling-rod, whereby the cars are automatically coupled. The outer side of plate D'' is beveled to opening d'', so as to direct the end of rod C into the opening in the draw-head when said rod and draw-head come together in other but a direct line, and the lower end of said plate is connected with the draw-bar d, and thereby strengthened, by means of an inclined rod d³.

The lever H is of such length as to extend slightly beyond or to the side of the car when horizontal, so as to obviate the necessity for entrance between the cars to uncouple, and may also be provided with a rod or chain H', whereby the lever may be raised by an operator on the car.

Each car is provided at each end with both members A and B, the member A on one end being arranged opposite the member B on the other end, the purpose of which is obvious.

In shifting cars it is frequently desirable that they be not coupled when brought together, and to this end I have provided the coupling with pins J, which are suitably hung from the forward plates or beams C³ and are adapted to enter openings j in said plates or beams adjacent to said levers H, and thereby hold the latter in vertical position when the latches are disengaged therefrom, and thus keep the heads c of rod C vertical. The coupling is also preferably provided with bumper-rods K, having encircling coil-springs K', which take up the shock incident to the shunting of the cars and to the bringing of the cars together, and thus assists in preventing injury to the couplings.

The draw-head D is supported and guided on ways D³, consisting of two rods projecting downward from the car-body beside the plate D' thereof and having inward-projecting ends upon which said plate rests and slides in its endwise movement.

I do not wish to be understood as limiting myself to the precise construction herein shown and described, as many of the details thereof may be altered or modified without departing from the spirit of the invention. For example, instead of making the draw-head of a horizontal and a vertical plate each

having an opening it may consist of a solid casting formed within its interior with a chamber of sufficiently-greater diameter than its mouth to leave shoulders immediately at the rear of said mouth for engagement of heads c of rod C.

Having now described my invention, I claim—

1. In a car-coupler, the combination of the draw-head, a weighted rod having a head at its outer end, a rock-shaft located adjacent to said rod and connected therewith, an uncoupling-lever connected with said rock-shaft, and a latch engaging said lever when the same is in raised position.

2. In a car-coupler, the combination of the draw-head having shoulders within its mouth, the weighted rod C, having a headed end, a rock-shaft connected with said rod, an uncoupling-lever connected with the said rock-shaft, and a spring-pressed latch engaging said lever when the same is in raised position, said latch having a projection designed to be engaged by the draw-head of the operating coupler when the cars are being brought together for coupling, for the purpose specified.

3. In a car-coupler, the combination of the draw-head having shoulders within its mouth, a rod having a headed end, a weight connected with one side of said rod, a rock-shaft having a disk, a chain connecting said disk with the side of said rod opposite said weight, an uncoupling-lever secured to the end of said rock-shaft, and a spring-pressed latch engaging said uncoupling-lever when the same is in raised position, said latch having a projection designed to be engaged by the draw-head on an approaching car, substantially as described, and for the purposes specified.

4. In a car-coupler, the combination of the draw-head having shoulders within its mouth, a weighted rod C, having a headed end, an uncoupling-lever connected with said rod and serving to partly rotate the same, and a spring-pressed latch engaging said uncoupling-lever when the same is in raised position, said latch having a projection designed to be engaged by the draw-head on an approaching car, substantially as described.

5. In a car-coupler, the combination of the draw-head having its draw-bar provided with an encircling coil-spring, the coupling-rod C, having an encircling coil-spring and provided on its outer end with a head, and spring-pressed bumper-rods movably supported beneath the car-body in line with the draw-head on the next adjacent car, all substantially as described, and for the purposes specified.

6. In a car-coupler, the combination of the draw-head having shoulders within its mouth, a weighted coupling-rod having a headed end, an uncoupling-lever connected with said rod, a spring-pressed latch engaging said lever

when the same is in raised position, said latch having a projection designed to be engaged by the draw-head on an approaching car, and a pin adapted to be inserted in an opening in the coupler adjacent to the lever when the same is in its raised position and serving to hold said lever in said position when the latch is disengaged therefrom, thereby rendering

the coupling inoperative, substantially as described.

In testimony whereof I affix my signature in presence of two witnesses.

THOMAS C. GIBSON.
